TO WESTERN WHEELED SCRAPER COMPANY, OF AURORA, ILLINOIS, A CORPORA-
TION OF ILLINOIS.

GRADING AND LOADING APPARATUS.

Application filed March 17, 1924. Serial No. 699,860.

Our invention relates to excavating apparatus for grading a roadway preparatory to subgrading for the paving of streets, and the loading of a vehicle with the earth removed 5 from the roadway during grading.

It is a purpose of our invention to provide a grading and loading apparatus of the above described character which is adapted for movement along a roadway, and which 10 operates while traveling to loosen the earth for a predetermined depth and elevate the same to a point where it can be discharged into a truck.

It is also a purpose of our invention to provide a grading and loading apparatus which is designed to be drawn by a motor truck which receives the earth discharged from the apparatus, thus utilizing the power of the truck for moving the apparatus so that when 20 the truck is filled it can be disconnected from the apparatus and a second truck connected to continue the grading operation and with it the loading of the second truck. In this manner a single apparatus is capable of successively loading a plurality of trucks, and 25 of utilizing the power of the trucks in moving the apparatus along a roadway.

A further purpose of our invention resides in the provision of a grading and loading apparatus the transverse dimensions of which 30 are such as to permit of its operating in narrow streets, alleys and highways or in any thoroughfare through which the truck drawing the apparatus is capable of traveling.

Another purpose of our invention is to provide a grading device adapted to be set into operation by forward movement of the apparatus, and a device which is adjustable to occupy any desired position for grading to 40 any predetermined depth, and to support the weight of the apparatus when necessary to insure proper operation of the device.

Further, our invention provides a pair of conveyors operating in conjunction with the 45 grading device to elevate the earth loosened for the purpose of loading a truck, the conveyors including a subsidiary conveyor which is flexibly supported to respond to roadway undulations and thus prevent injury to the 50 main conveyor and its support, yet maintaining proper operative relation to the main conveyor and to the grading device.

We will describe only one form of grad-

ing and loading apparatus embodying our invention, and will then point out the novel 55 features thereof in claims.

In the accompanying drawings:

Figure 1 is a view showing in side elevation one form of grading and loading apparatus embodying our invention; 60

Figure 2 is an enlarged fragmentary view showing in side elevation the plow side of the apparatus shown in Figure 1;

Figure 3 is a view showing in rear end elevation the apparatus shown in the preceding 65 views;

Figure 4 is a vertical sectional view taken on the line 4—4 of Figure 3;

Figure 5 is a fragmentary plan view of the rear end of the apparatus shown in the preceding 70 views;

Figure 6 is a sectional view taken on the line 6—6 of Figure 1;

Figure 7 is a view, partly in section, showing the plow side of the subsidiary conveyor 75 comprised in the apparatus;

Figure 8 is a fragmentary plan view of the lower end of the main conveyor comprised in the apparatus;

Figure 9 is a fragmentary view showing 80 in side elevation the lower end of the main conveyor;

Figure 10 is an enlarged vertical sectional view of the yieldable connection between the grading device comprised in the apparatus 85 and the means for adjusting the forward end of such device.

Similar reference characters indicate corresponding parts in each of the several views 90 of the drawings.

Referring specifically to the drawings, and particularly to Figure 1, our invention in its present embodiment is shown as comprising a vehicle chassis or frame C, of rectangular form and made up of channel beams riveted 95 or otherwise secured to each other at their ends. The chassis C is supported for movement by rear wheels W rigidly associated with the chassis through brackets B, and front wheels W' associated with the chassis to allow vertical movement thereof through the medium of semi-elliptical springs S interposed between the front axle and relatively short beams E rigidly connected to the chassis. A conventional steering mechanism is associated with the wheels W', to effect steer- 100 105

ing of the latter, and this mechanism includes a steering wheel D arranged at one side of the vehicle, as clearly shown in Figure 1, and in advance of a seat F adapted to be occupied by one of the operators of the apparatus.

Secured upon the forward end of the chassis C is an arch A which is designed to pivotally support the main conveyor of the apparatus designated generally at M. This main conveyor comprises in the present instance spaced parallel beams 15, which are rigidly connected at regular spaced intervals along their length by means of channel irons 16. Also arranged at regular spaced intervals along the length of the beams 15 are groups of rollers 17, which, as clearly shown in Figure 6, are rotatably mounted in brackets 18 secured to cross rails 19. The rollers of each group are arranged to produce a continuous supporting surface over which an endless belt 20 is adapted to move, the rollers serving to support the belt in trough formation throughout its carrying length so that the earth deposited thereupon cannot scatter and spill over the sides but is held in a compact furrow to permit its being elevated at a much greater angle than otherwise. This belt 20 is trained about a lower or driven roller 21 and an upper or driving roller 22, the latter being adapted to effect continuous movement of the belt, with the upper stretch thereof moving upwardly over the groups of rollers 17, while the lower stretch moves downwardly over idlers 23 journaled in brackets 24, as clearly shown in Figure 6.

The main conveyor as a unit is supported to normally occupy an inclined position as illustrated in Figure 1, so as to be capable of rocking movement to permit vertical adjustment of the lower end of the conveyor. To this end, plates 25 are secured to the confronting sides of the beams 15, and journaled in these plates are stub shafts 26 secured to the arch A. The main conveyor is thus mounted to swing about the stub shafts as a center, and it will be particularly noted that the mounting is in advance of the medial point of the conveyor so that it normally tends to occupy an inclined position.

For driving the belt 20 of the main conveyor the driving roller 22 is actuated by a conventional form of motor T suitably supported on the chassis and provided with a variable speed transmission V which is operatively connected to the driving roller 22 by means of shafts 27 and 28 connected to each other by a universal joint 29 supported on the arch A. The other end of the shaft 27 is connected to the transmission V through a universal joint 30, while the upper end of the shaft 28 is connected to the driving roller 22 by an extensible connection 30a. These shafts and joints permit driving of the roller 22 irrespective of the position of the main conveyor M.

For the purpose of adjusting the lower end of the conveyor M so that it may occupy proper position with respect to a roadway, we provide a pair of chains 31 connected to the conveyor at their lower ends and to a shaft 32 at their upper ends. This shaft 32 is adapted to be rotated in either direction to wind or unwind the chains thereupon and to thereby raise or lower the lower end of the conveyor to the desired level. This shaft 32 is provided with a worm gear 33 (Figure 2) which constantly meshes with a worm 34 fixed to the forward end of a shaft 35. The rear end of the shaft 35 is provided with a hand wheel 36 arranged in advance of a platform 37 upon which an operator is adapted to stand when manipulating this and other hand wheels.

As illustrated to advantage in Figures 1, 3 and 5, the lower end of the main conveyor M is provided with a hopper 38 into which earth from a subsidiary conveyor is adapted to be discharged on to the endless belt 20. This hopper serves to guide the earth onto the belt and to prevent discharge of earth from the lower end of the belt. Guard rails 39 supported on brackets 40 (Figure 6) are arranged above and at the opposite edges of the belt 20, which serve to confine the earth upon the belt, as will be understood.

As shown in Figures 1 and 9, the lower ends of the side beams 15 of the main conveyor are tapered in width, and secured to these tapered ends is a tie plate 41 to the lower end of which is secured a shoe 42. The lower end of the plate 41, as well as the shoe 42, is curved so that the latter, when in engagement with the roadway, will not impede the progress of the apparatus and at the same time will prevent wear of the beams themselves.

Referring now to Figures 3, 5 and 7, M' designates generally a subsidiary conveyor designed for the purpose of carrying earth from the grading device and depositing the same onto the lower end of the main conveyor M. As the specific construction of the subsidiary conveyor is to form the subject matter of a separate application, only those parts of the conveyor necessary to a clear understanding of the present invention will be described.

The subsidiary conveyor M' comprises in the present instance a frame 43 carrying a lower driven roller 44 and an upper driving roller 45. Trained about these rollers is an endless belt 46 which rotates in such direction as to carry the earth upwardly of the conveyor, discharging the same onto the main conveyor. The driving roller 45 is operatively connected to a vertical shaft 47 through the medium of a splined connection 48 which permits of the necessary vertical movement between the shaft and the roller without affecting the driving connection between the two.

The upper end of the vertical shaft 47 is operatively connected to a horizontal shaft 49 (Figure 3) through suitable gearing and a universal joint 50, the latter serving to allow the necessary lateral shifting movement of the shaft 47 to permit the required movement of the subsidiary conveyor. The shaft 49, in turn, is driven from the transmission V through the third shaft 51, as shown in Figure 1.

The belt 46 of the subsidiary conveyor may be provided with transverse ribs 52 which, during the movement of the belt, serve to prevent slippage of the earth on the belt and thus insure upward travel of the earth, as will be understood. To confine the earth upon the belt during transit guard plates 53 extend upwardly from the opposite sides of the conveyor frame as clearly shown in Figure 7. The lower end of the conveyor frame is provided with an angle bar 54 which carries a wear plate 55 adapted to have contact with the roadway during the operation of the apparatus. As shown in Figure 5, the lower forward side of the subsidiary conveyor is provided with a deflector plate 56 which is designed to co-operate with the grading device in directing earth onto the belt of the subsidiary conveyor.

As the lower end of the subsidiary conveyor is adapted to have continuous engagement with the roadway, it is necessary that the conveyor be flexibly supported to respond to the undulations of the roadway and thus prevent injury to the conveyor and the associated parts, and at the same time to maintain a definite relative position with respect to the main conveyor M. To this end we have provided the mounting shown to advantage in Figures 7, 8 and 9, which, in the present instance, comprises a strap iron 57 extending transversely and upwardly, with respect to the lower end of the main conveyor. The upper end of the strap 57 is connected to straps 58 and 59 which serve to rigidly support a pin 60 in definite position with respect to the main conveyor. A second pin 61 formed on the upper end of a strap 62 secured to the main conveyor M is disposed in longitudinal alignment with the pin 60, as indicated by the dot and dash lines in Figure 9. The pin 61 extends into a slot 63 of a plate 64 secured to the subsidiary conveyor frame 43, as clearly shown in Figure 7. The other pin 60 extends into a slot 65 of a plate 66 on the opposite edge of the subsidiary conveyor frame.

It is by means of these pin and slot connections just described that the subsidiary conveyor M' is capable of limited longitudinal movement without disturbing the position of the main conveyor M, it being remembered that the subsidiary conveyor is free to move longitudinally by virtue of the splined and universal connections between the driving

roller and the shafts for actuating the latter. These pin and slot connections also serve to allow limited vertical movement of the lower end of the main conveyor M without disturbing the relative position of the subsidiary conveyor.

The grading device embodied in our apparatus is designed to plow the roadway to a predetermined depth, depending upon the adjustment of the device, and under the traveling movement of the apparatus to elevate the earth plowed so that it may be deposited upon the subsidiary conveyor M'. The device for accomplishing these functions comprises in the present embodiment a heavy duty plow having a blade 67 pointed at its forward end and widened and curved inwardly at its rear end, as clearly shown in Figure 5, so as to direct the earth onto the belt of the subsidiary conveyor. This plow blade is secured to an arm 68 depending from a bracket 69 secured to one of a pair of channel bars 70, constituting the plow beam. It will be noted that the forward edge of the arm 68 is relatively sharp to provide a cutting edge 68a for the purpose of cutting the earth along the outer side of the furrow formed by the plow. A bar 71 extends rearwardly from the arm 68 (Figure 2) and connects the latter with a second arm 72 depending from and interposed between the bars 70. A main supporting plate 73 depends from the plow beam 70 and is secured to the bar 71 between the arms 68 and 72, and co-operates with the latter to provide a rigid supporting means for the plow. As shown in Figure 2, the beam 70 serves to support a gauge wheel 74 arranged in advance of the plow blade and adapted to ride upon the roadway for partly regulating the depth of penetration of the plow blade. This wheel 74 is supported upon a plate 75 loosely fitted between the channel bars 70 and adapted to be adjustably secured therebetween by means of a pin 76 which can be extended through any one of a plurality of openings formed in the bars and plate. The arrangement of the openings is such that not only a vertical but a horizontal adjustment of the gauge wheel can be secured.

The plow blade 67 and its supporting means, although being capable of vertical and horizontal adjustment, are adapted to be securely held against longitudinal movement in either direction, and to this end a rod 78 is pivotally and adjustably connected to a plate 79 secured between the channel bars 70, as clearly shown in Figure 2. The forward end of the rod 78 is connected to a depending bracket 80 (Figure 1) through a turnbuckle 81 whereby proper tension may be exerted upon the rod so that it will properly function to secure the plow and its supporting means against rearward movement with respect to the apparatus. A chain 82 or its equivalent is connected to the rear ends of the beam 70

and to a bracket 83 depending from the chassis C. This chain may also be adjusted so as to secure the plow and its supporting means against forward movement with respect to 5 the apparatus.

To effect vertical adjustment of the rear end of the plow and its supporting means, and to positively hold the plow in juxtaposition to the vehicle frame and the auxiliary 10 conveyor, we have provided a substantially J-shaped beam or channel bar 84 which, as shown in Figure 3, is arranged transversely of the apparatus beneath the chassis C and with its upper end pivotally connected to the 15 chassis through the medium of an I-strap 85 and a U-bolt 86. The lower end of the beam 84 is also provided with an I-strap 87 through which extends a U-bolt 88 carried by a bracket 89 secured to the arm 72. This beam 84 is 20 adapted to be lowered or elevated through the medium of a connecting rod 90 pivotally connected, as at 91, to the beam, and having a crank connection 92 with a worm gear 93 fixed to a shaft 94. A worm 95 meshes with 25 the worm gear 93 and is fixed to a shaft 96 adapted to be rotated by a hand wheel 97, whereby the gear 93 is rotated in one direction or the other to lower or elevate the rod 90 to vary the vertical position of the beam 84. 30 By virtue of the connection between the plow supporting means and the beam 84 it will be clear that vertical adjustment of the latter will effect a corresponding vertical adjustment of the rear end of the plow beam.

35 To effect vertical adjustment of the forward end or point of the plow a pressure or resilient connection designated generally at K is pivotally connected to the plate 79 and to a crank arm 98 on one end of a shaft 99. The 40 shaft 99 is provided with a worm gear 100 meshing with a worm 101 fixed to an inclined shaft 102. The shaft 102 is also provided with a beveled pinion 103 which constantly meshes with a beveled ring gear 104 (Figure 45 3) fixed to a hand wheel 105. The gear 104 and wheel 105 are loosely mounted on the shaft 96 so that they can be rotated independently of the shaft to effect rotation of the shaft 102. With the rotation of the shaft 102 50 the crank arm 98 is rotated to lower or elevate the forward end of the plow beam 70 through the medium of the pressure connection K.

The resilient connection K is designed for 55 the purpose of exerting a constant but yielding pressure on the forward end of the plow beam to assist in holding the gage wheel in firm contact with the ground to secure an even depth of furrow, particularly when the 60 gage wheel and vehicle wheels are traveling in different or uneven planes. As shown in Figure 10, the connection K comprises a rod 118 provided at its lower end with an eye 119 engaged by a U-bolt 120 for pivotally securing the rod to the plate 79. The rod 118 is

movable in a cylindrical sleeve 121 and is centered therein by means of an enlargement 122 into which latter extends a screw 123 movable in a slot 121^a of the sleeve for preventing rotative movement of the rod in the sleeve. 70 The upper end of the rod 118 extends into a second sleeve 124 fixedly secured in the upper end of the sleeve 121. A guide member 125 is secured within the sleeve 121 beneath the sleeve 124 and slidably receives the rod 118. 75 The upper end of the rod 118 is threaded to receive nuts 126 which can be adjusted to limit the downward movement of the rod 118 by engaging the member 125. Upward movement of the rod is limited by a flange 126^a 80 formed thereon and providing an abutment to engage the lower end of the sleeve 121. The upper end of the sleeve 124 receives a head 127 secured therein by means of a pin 128, and this head carries a fork 129 which is pivotally 85 connected to the crank arm 98 through a pin 130.

The sleeve 121 is supported for vertical movement by a brace rod 131 (Figure 5) connected to one of the beams of the chassis and 90 having pivotal connection with a bracket 132 embracing the sleeve 121.

A spring 133 surrounds the rod 118 between the enlargement 122 and the guide 125 and operates to normally urge the rod downwardly to set up the desired pressure upon the plow beam. It will be understood that the pressure exerted on the rod can be varied through an adjustment of the crank arm 98, causing vertical adjustment of the sleeves to 100 compress the spring 133 any degree desired. When the adjustment of the sleeves is such that the nuts 126 engage the guide member 125, or the sleeve 121 engages the flange 126^a, the connection between the crank arm 105 and the plow beam becomes rigid and unyielding so as to provide, in the first instance, a positive connection between the two to permit raising of the plow point, and, in the second instance, a rigid connection 110 through which the entire weight of one side of the apparatus can be thrown onto the plow.

By means of the resilient connection K and the beam 84, it will be manifest that either end of the plow can be adjusted downwardly 115 to such an extent as to actually lift one side of the vehicle and thus apply the weight of one side of the vehicle either to the point or to the heel of the plow, so that the plow point may be forced into the ground irrespective of the impenetrable character of the ground.

As previously stated, the grading device including the plow and its supporting means is also capable of lateral adjustment or side tilting for the purpose of varying the angle 125 at which the plow point enters the earth when opening a new furrow. The means for effecting this lateral adjustment comprises a strap 106 (Figures 2 and 3) secured to and 130 extending upwardly from the rear end of the

channel bar 70. A connecting rod 107 pivotally connects the upper end of the strap 106 with an operating lever 108 pivoted at 109 so as to effect longitudinal movement of the 5 rod and a resultant lateral movement of the strap, whereby the position of the plow with respect to a longitudinal vertical plane is capable of being varied. The lever 108 is adapted to be releasably secured in any 10 adjusted position by means of a hand operated pawl 110 engaging a rack 111.

To brace the subsidiary conveyor M' and the beam 84 against rearward movement with respect to the vehicle chassis, while at the 15 same time in no way hampering vertical or lateral adjustment thereof, rods 112 and 113 are provided, the rod 112 pivotally connecting the plate 79 with the angle bar 54 (Figure 5), and the said rod 113 pivotally connecting 20 the bracket 114 secured to the chassis C with the beam 84.

Referring again to Figure 3, we have shown a yoke 115 secured to the plow blade 67 and shaped as illustrated in Figure 4, with 25 a slotted I-bolt 116 movable on the vertical portion of the yoke and secured to the angle bar 54. This connection causes the lower end of the subsidiary conveyor to move vertically with the plow when the latter is lifted, but 30 nevertheless allows the lower end of the subsidiary conveyor to move vertically without disturbing the position of the plow blade and its supporting means, and the conveyor can thus respond to undulations in the road- 35 way, while the plow occupies a fixed position, without subjecting the conveyor and its associated parts to undue stresses or strains. It will be understood that the connection is such 40 as to restrict the vertical movement of the conveyor only sufficiently to maintain the conveyor in earth receiving position with respect to the plow blade. This connection also allows a limited longitudinal movement 45 of the plow and its supporting means, which is necessary when vertically adjusting one end or the other of the plow; otherwise the yoke 115 would bind within the I-bolt 116, and lock the plow against such adjustment.

As shown in Figure 1, a draft beam 134 50 is mounted on the forward end of the chassis, and carries a coupling device H which can be operated to release a coupling pin of a motor truck by operation of a lever L. The coupling device is to form subject matter of 55 another application and will not, therefore, be described in detail herein.

The operation of the entire apparatus is as follows:

A truck, preferably a motor truck, is connected to the front end of the apparatus 60 through the draft beam 134 so that the forward or upper end of the main conveyor is in overlying relation with respect to the body of the truck. Forward movement of the 65 truck effects a corresponding movement of

the apparatus, and with the plow blade 67 lowered to penetrate the earth, forward movement of the plow will cause the earth to be loosened and moved rearwardly and upwardly of the plow blade, and finally deposited on 70 to the belt 46 of the subsidiary conveyor M'. Before the apparatus is under way the belts of the main and subsidiary conveyors are set into motion by proper manipulation of the transmission V, as will be understood. With 75 these belts continuously moving, earth deposited upon the subsidiary conveyor belt will be carried upwardly of the conveyor and deposited onto the belt of the main conveyor. The earth deposited upon the main 80 conveyor is carried upwardly and finally discharged from the upper end of the conveyor into the body of the motor truck.

After the truck is loaded it is disconnected from the apparatus and a second truck connected to the latter so that upon continued movement of the apparatus a loading of the second truck can be effected. In this manner 85 any number of motor trucks can be successively loaded with the apparatus, utilizing the 90 power of each truck to the extent of hauling the grading device or plow.

Although we have herein shown and described only one form of grading and loading apparatus embodying our invention, it 95 is to be understood that various changes and modifications may be made herein without departing from the spirit of the invention and the spirit and scope of the appended claims.

What is claimed is:

1. A grader and loader comprising a vehicle, a plow adjustably carried on the vehicle for removing earth from a roadway, a main conveyor adjustably sustained on the vehicle, and a subsidiary conveyor movably supported on the vehicle and connected with the plow so that its lower end will move vertically with the plow and may engage the ground and move vertically without disturbing the position of the plow in response to 105 undulations of the ground, said plow being constructed and arranged to discharge the plowed earth laterally on to said subsidiary conveyor, said latter conveyor discharging the removed earth to said main conveyor. 110

2. A grading and loading apparatus comprising a vehicle, a plow depending from the vehicle, an inclined main conveyor extending longitudinally of and pivoted on the vehicle, and a subsidiary conveyor on and extending 120 transversely of the vehicle, said subsidiary conveyor being mounted for longitudinal, vertical and pivotal movements.

3. In a grading and loading apparatus, a vehicle, a plow depending from said vehicle, 125 a main longitudinally extending conveyor fulcrumed between its ends on said vehicle to permit vertical rocking movement thereof, and a subsidiary conveyor arranged to convey the earth from said plow to said main 130

conveyor, and having a connection with the main conveyor which permits freedom of movement of the two conveyors independently of each other while maintaining a definite relation between the two.

4. In a grading and loading apparatus, a vehicle, a main conveyor mounted on the vehicle to normally occupy an inclined position, and a subsidiary conveyor at an angle to the lower end of the main conveyor and normally occupying an inclined position with its lower end adapted to contact with a roadway, said subsidiary conveyor being mounted to permit its lower end to move vertically and the entire conveyor to move longitudinally.

5. A grading and loading apparatus comprising a vehicle, a plow sustained on the vehicle to move vertically and laterally, means for moving to and securing the plow in any position which it is capable of occupying, a main conveyor fulcrumed between its ends to permit vertical rocking movement thereof, and a subsidiary conveyor having a connection with the main conveyor which permits freedom of movement of the two conveyors independently of each other while maintaining a definite relation between the two.

6. A grading and loading apparatus comprising a vehicle, a plow sustained on the vehicle to move vertically and laterally, means for moving to and securing the plow in any position which it is capable of occupying, a main conveyor mounted on the vehicle to normally occupy an inclined position, and a subsidiary conveyor at an angle to the lower end of the main conveyor and normally occupying an inclined position with its lower end adapted to contact with a roadway, said subsidiary conveyor being mounted to permit its lower end to move vertically and the entire conveyor to move longitudinally.

7. In a grading and loading apparatus, a vehicle, a plow mounted on the vehicle for universal adjustment, a main conveyor pivoted on the vehicle, and a subsidiary conveyor for conveying earth from the plow to the main conveyor, both of said conveyors being adapted to contact with a roadway, said subsidiary conveyor being mounted to respond to undulations in the roadway independently of the plow and main conveyor.

8. In a grading and loading apparatus, a vehicle, a plow mounted on the vehicle for vertical adjustment, a main conveyor adjustably mounted on the vehicle so as to respond to the undulations in the roadway, and a subsidiary conveyor having contact with the roadway and mounted on the main conveyor to move with the latter and to respond to the undulations in the roadway and independently of the main conveyor.

9. In combination, a vehicle, and a conveyor pivoted on the vehicle so as to occupy an inclined position, with one end adapted to contact with a roadway and free to respond to.

undulations of the roadway, a second conveyor arranged at an angle to the lower end of the first conveyor, said second conveyor having one end above the lower end of the first conveyor and the other end in contact with the roadway, and a pivotal and slidable connection between the two conveyors permitting the second conveyor to respond to undulations in the roadway without disturbing the position of its upper end with respect to the first conveyor.

10. A grader and loader comprising a vehicle, a plow, conveying means arranged to receive the dirt from said plow and to convey the same forwardly for dumping into a truck in advance of the grading and loading vehicle and means supporting the plow at one side of the vehicle, said supporting means being adjustably adapted to serve as a rigid strut between the vehicle and plow whereby the weight of one side of the vehicle can be applied to or removed from either the point or the heel of the plow.

11. In combination, a vehicle, a plow, and means for supporting the plow at one side of the vehicle and in adjustable relation thereto, said means including a yielding pressure connection adjustable to vary the pressure exerted by the connection on the plow and to provide a rigid connection when in certain positions.

12. In combination, a vehicle, a plow, and means for adjustably supporting the plow on the vehicle, said means including a yielding pressure connection adjustable to vary the pressure exerted by the connection on the plow and to provide a rigid connection when in certain positions.

13. In a grading and loading machine, the combination of a vehicle, a plow, and means for supporting the plow at one side of the vehicle and in adjustable relation thereto, said means including controlling devices actuatable by the operator while the machine is in operation whereby the weight of one side of the vehicle can be applied controllably to the point or heel of the plow.

14. In a grading and loading apparatus, the combination of a main conveyor, a subsidiary conveyor pivotally and slidably connected to the main conveyor, a plow connected to the subsidiary conveyor for limited movement longitudinally and transversely of the conveyor, and means for adjusting the plow vertically as a unit and either end of the plow.

15. In a grading and loading apparatus as embodied in claim 14, wherein said adjusting means includes a beam mounted for pivotal movement and hingedly connected to the plow.

16. In a grading and loading apparatus, the combination of a pivoted conveyor, a plow, means for vertically adjusting the plow, and a connection between the plow

and conveyor to allow limited relative movement of the plow but to maintain the conveyor in definite relation to the plow.

17. In a grading and loading apparatus, 5 the combination of a pivoted conveyor, a plow, means for vertically adjusting the plow, and a hinge connection between the plow and conveyor to allow limited relative movement of the plow but to maintain the 10 conveyor in definite relation to the plow.

18. In a grading and loading apparatus, a vehicle, a plow mounted on the vehicle for vertical and lateral adjustments, a conveyor supported for vertical movement to respond 15 to vertical adjustment of the plow and adapted to receive earth elevated by the plow, and means for connecting the conveyor to the plow so that the conveyor will occupy a definite earth receiving position with respect 20 to the plow irrespective of the adjustment of the latter.

19. In a grading and loading apparatus, a main conveyor supported for pivotal movement, a subsidiary conveyor pivotally and 25 slidably connected to the main conveyor, and a plow connected to the subsidiary conveyor for limited movement longitudinally and transversely of the subsidiary conveyor.

20. In a grading and loading apparatus, 30 a main conveyor supported for pivotal movement, a subsidiary conveyor pivotally and slidably connected to the main conveyor, a plow connected to the subsidiary conveyor for limited movement longitudinally and trans- 35 versely of the subsidiary conveyor, and means for adjusting the plow, including a beam mounted for pivotal movement and hingedly connected to the plow.

21. In a grading and loading apparatus, a 40 main conveyor, a subsidiary conveyor, a plow, a connection between the conveyors for maintaining the two in operative relation but allowing limited independent movement of each, and a connection between the plow and subsidiary conveyor by which the two are 45 maintained in operative engagement but free to move independently of each other.

22. A grading and loading apparatus comprising a vehicle, a plow sustained on the vehicle to move vertically and laterally, means for moving said plow to different positions and for securing it in these positions, a main conveyor fulcrumed to the vehicle to permit vertical pivotal movement thereof, 55 and a subsidiary conveyor having a connection with the main conveyor which permits freedom of movement of the two conveyors independently of each other while maintaining a definite relation between the two.

23. A grading and loading apparatus comprising a vehicle, a plow sustained on the vehicle, means for moving said plow to different positions and for securing it in these 60 positions, a main conveyor supported on the vehicle, and a subsidiary conveyor having a

connection with the main conveyor which permits relative movement between the two conveyors while maintaining a definite relation between the two.

24. A grading and loading apparatus comprising a vehicle, a plow sustained on the vehicle, means for moving said plow to different positions, and for securing it in these positions, a main conveyor pivotally connected to the vehicle to permit pivotal movement of the conveyor, and a subsidiary conveyor having a connection with the main conveyor which permits freedom of movement of the two conveyors independently of each other while maintaining a definite relation between the two. 70 75

25. In a grading and loading apparatus, a vehicle, a plow mounted on the vehicle for vertical adjustment, a laterally extending conveyor supported for vertical movement to respond to vertical adjustment of the plow 80 and adapted to receive earth elevated by the plow, a secondary conveyor receiving the earth from said laterally extending conveyor and means for connecting the laterally extending conveyor to the plow so that said conveyor will occupy a definite earth receiving position with respect to the plow irrespective of the adjustment of the latter. 85 90

26. In a grading and loading apparatus, 95 a vehicle, a plow mounted on the vehicle for vertical adjustment, a laterally extending conveyor supported for vertical movement to respond to vertical adjustment of the plow and adapted to receive earth elevated by the 100 plow, a forwardly extending conveyor adapted to receive the earth from said laterally extending conveyor, one of said conveyors being adjustable and the other conveyor moving therewith in such adjustment and means 105 for connecting the laterally extending conveyor to the plow so that said conveyor will be maintained in definite earth receiving position with respect to the plow irrespective of the adjusting movement of the plow or of 110 the conveyors.

27. A grading and loading apparatus comprising a vehicle, a plow sustained on the vehicle, means for moving said plow to different positions, a main conveyor movably supported on said vehicle, a subsidiary conveyor flexibly supported on said vehicle for yielding contact with the ground independently of movement of the plow, means for maintaining said subsidiary conveyor in earth 115 receiving position relative to said plow through a predetermined adjusting range of said plow, and means for maintaining said main and subsidiary conveyors in definite earth transferring relation while permitting 120 relative movement bodily between said conveyors. 125

28. In a grading and loading machine, a main conveyor arranged to discharge forwardly of the machine and pivotally sup- 130

- ported to permit vertical pivotal movement thereof, and a subsidiary conveyor having connection with the main conveyor which permits freedom of movement of the two conveyors independently of each other while maintaining a definite relation between the two.
29. In a grading and loading apparatus, a vehicle grading means carried thereby, a main conveyor arranged to discharge from one end of the vehicle, said main conveyor being pivotally supported on said vehicle to permit vertical pivotal movement thereof, and a subsidiary conveyor supported on said vehicle for limited longitudinal movement for maintaining a definite relation between said two conveyors, said subsidiary conveyor transferring the earth from said grading means to said main conveyor.
30. A grading and loading apparatus comprising a vehicle, a plow supported on the vehicle for vertically adjustable movement, a conveyor extending transversely of the vehicle, and means connecting said plow with said conveyor, said connecting means causing upward movement of the lower end of said conveyor with upward movement of said plow, but permitting upward movement of the lower end of said conveyor independently of said plow.
31. A grading and loading apparatus comprising a vehicle, a plow adjustably supported on said vehicle for vertical movement, a conveyor extending transversely of said vehicle with its lower end in earth receiving position relative to said plow, and means for connecting said plow to the lower end of said conveyor, said means causing the lower end of said conveyor to rise with the upward movement of said plow, but permitting upward movement of the lower end of said conveyor independently of said plow.
32. A grading and loading apparatus comprising a vehicle, a plow, means supporting the plow at one side of the vehicle, said supporting means being adjustably adapted to serve as a rigid strut between the vehicle and plow whereby the weight of one side of the vehicle can be applied to or removed from the plow, a conveyor movably supported on the vehicle with one end in earth receiving position relative to said plow, and means for connecting said plow to said conveyor, said means causing upward movement of said conveyor with the upward movement of said plow, but permitting upward movement of said conveyor independently of said plow.
33. A grading and loading apparatus comprising a vehicle, a main conveyor pivotally supported on said vehicle for vertical pivotal movement, a subsidiary conveyor extending substantially transversely of said main conveyor and adapted to discharge earth at one end thereof to said main conveyor, and means for connecting the latter end of said subsidiary conveyor to the adjacent portion of said main conveyor, said means comprising a slotted connection for maintaining said conveyors in predetermined operative relation during the adjustment of one of said conveyors.
34. A grading and loading apparatus comprising a vehicle, a plow adjustably supported on said vehicle, a subsidiary conveyor movably supported on said vehicle and adapted to receive earth from said plow, said subsidiary conveyor having one end normally resting on the ground, and a main conveyor adapted to receive earth from said subsidiary conveyor and extending longitudinally of said vehicle.
35. A grading and loading apparatus comprising a vehicle, a plow mounted on said vehicle, a main conveyor mounted on said vehicle, a subsidiary conveyor for receiving earth from said plow and transferring it to said main conveyor, said subsidiary conveyor being movably supported on the vehicle, a shaft for transmitting a power drive to said subsidiary conveyor, and an extensible connection in said shaft for permitting movement of said subsidiary conveyor.
36. A grading and loading machine comprising a wheeled vehicle frame, a plow comprising a plow beam, a conveyor extending longitudinally of the vehicle frame for discharging into a secondary vehicle at one end of said grading and loading machine, means for transferring the earth from said plow to said conveyor, and means adjustably connecting the plow beam to said vehicle frame whereby the weight of the vehicle may be utilized to force either end of the plow down into the ground.
37. A grading and loading machine comprising a wheeled vehicle frame, a plow comprising a plow beam, a main conveyor extending longitudinally of said vehicle frame for discharging into a secondary vehicle moving in advance of said grading and loading machine, a subsidiary conveyor extending transversely of said vehicle frame for transferring the earth from said plow to said main conveyor, depth adjusting means adjustably connecting the rear portion of said plow beam to said vehicle frame and operative to utilize the weight of the vehicle for forcing the heel portion of the plow down into the ground, and separate depth adjusting means adjustably connecting the front portion of said plow beam to said vehicle frame and operative to force the toe portion of the plow down into the ground.
38. A grading and loading machine comprising a wheeled vehicle frame having an operator's position thereon, a plow comprising a plow beam, a main conveyor extending forwardly of the vehicle frame for discharging into a secondary vehicle traveling in advance of said grading and loading machine, a subsidiary conveyor extending trans-

versely of said vehicle frame for transferring the earth from said plow to said main conveyor, depth adjusting means connecting the rear portion of said plow beam to said vehicle frame and actuatable from the operator's position while the machine is in operation for imposing a portion of the weight of the vehicle on the heel portion of said plow, and independently operating depth adjusting means connecting the front portion of the plow beam to said vehicle frame and actuatable from the driver's position while the machine is in operation for imposing the weight of the vehicle on the toe portion of said plow.

39. A grading and loading machine comprising a vehicle, a plow adjustable on the vehicle for removing earth from a roadway, a main conveyor adjustable on the vehicle and extending forwardly thereof for discharging into a secondary vehicle in front of said grading and loading machine, a subsidiary conveyor adjustable on and extending transversely of said grading and loading vehicle, and means for driving said conveyors irrespective of their adjusted positions.

40. A grading and loading machine comprising a vehicle, a plow depending from and extending lengthwise of the vehicle, a main conveyor pivoted on the vehicle for adjustment about a horizontal axis and extending parallel to the plow and forwardly of said vehicle for dumping into a secondary vehicle in front of said grading and loading machine, and a subsidiary conveyor on said grading and loading vehicle disposed substantially at right angles to the plow and main conveyor for transferring the earth from said plow to said main conveyor.

41. A grading and loading machine comprising a vehicle, a plow depending from the vehicle, an inclined main conveyor pivoted on said vehicle and extending longitudinally thereof for discharging from one end of the vehicle, and a subsidiary conveyor extending transversely of the vehicle and arranged to transfer the earth from said plow to said main conveyor, said subsidiary conveyor being mounted for movement bodily independently of the main conveyor.
